UNITED STATES PATENT OFFICE.

FREDERICK S. RAY, OF PEMBROKE, MASSACHUSETTS.

DRYING RACK.

Application filed January 6, 1925. Serial No. 905.

The invention relates to an improvement in drying racks and essentially to racks of a portable character useful in the drying of skins arranged upon frames.

5 The purpose of the invention is to provide a generally improved means for holding separate from one another the frames upon which the skins are arranged.

The invention can best be seen and understood by reference to the drawings, in which—

10 Figure 1 is a side elevation of a drying rack embodying the present invention.

Fig. 2 is a front elevation of the same.

15 Fig. 3 is a plan showing the arrangement of the fingers and mounting therefor, which fingers operate as the immediate means for holding separate the frames upon which the skins are arranged. This plan is from one 20 side of the rack only, the other side being identical in character.

Fig. 4 is a section on the line 4—4 of Fig. 3, the finger there shown being in an operative position, and

25 Fig. 5 is the same as Fig. 4 excepting that the finger there shown is occupying an inoperative out-of-the-way position.

Referring to the drawings:—

1 represents the body or base of the rack 30 preferably consisting of a low flat-topped truck provided with wheels 2 by which it may be moved about. The truck forms the chief support for the skins 3 each of which is tacked to a frame 4 preferably rectangular in form. These frames with attached skins will hereinafter be referred to as drying units.

The truck is adapted to carry a considerable number of the drying units which are 40 arranged on end in an upright position in line with one another. The units are spaced from one another in order that air may freely circulate between them. The units are also preferably arranged in sets on opposite sides of an interposed frame structure or fixture 5 secured to the truck. The units are also arranged to lie between side rails 6 extending parallel with the truck and lying some distance above it. These side rails 50 are secured to the opposite sides of the fixture 5 and provide not only a lateral support for the units, but carry also fingers 7 against which the inclined units rest and which fingers operate to hold the units in place properly spaced from one another. When in place resting on the truck the bot-

tom ends of the respective units are placed in contact with one another and the spacing and retention of the units by the fingers 7 are such that each set of units will present a 60 substantially fan-shaped appearance.

Each of the side rails 6 has the form of a channel bar with inner and outer sides 8 and 9, respectively, and bottom 10. The rails are each preferably made in two sections 65 fastened together by rivets 11.

Formed in the bottom 10 of each of the rails are a series of openings 12 which correspond in number with the number of the respective fingers 7 with which the rail is 70 provided. The openings 12 are located just forward of the outer side 9 of the rail.

Adjacent the openings 12 and lying just above them the rails are provided with mountings 13 which form supports for the 75 respective fingers. These mountings consist preferably of rods extended over the respective openings in the bottoms of the rails from which the mountings are spaced and the rods are secured to the bottoms of the 80 rails by providing the rods with turned threaded ends 14 passed through the bottom of the rail to which the mounting is adjacent and secured to it by clamping nuts 15.

The fingers 7 are each preferably reinforced along the back by an edge or flange-forming portion 16 for strengthening the finger, turned preferably as shown. Each of the fingers is provided with a turned outer end 17 much in the manner of a hook 90 with a squared heel portion 17'. The end 17 is adapted to pass around one of the mountings 13 to which the finger is adjacent whereby the finger may turn pivotally on such mounting. Forward of the end 17 the 95 finger is provided with a drawing edge portion 18, by which it may draw over the mounting as will later be explained, and beyond the edge 18 with a shoulder 19. The relative size and arrangement of the fingers 100 is such that when the fingers are in their downturned operative position, as shown in Fig. 4, with the outer curved end of the fingers embracing their mountings, the fingers will then extend from their mountings 105 in a substantially horizontal direction over the inner side 8 of the rail and thence beyond the inner face of the rail in sufficient amount to enter the line of drying units and operate as space and retaining members for the 110 respective units. When thus disposed the body of each finger will lie in a slot 20 cut in the

inner side 8 of the rail with the edge 18 of the finger resting on the side of the rail at the bottom 21 of the slot. The shoulder 19 of the finger will then lie just forward of the side of the rail on which the finger is resting. The end 17 of the finger will extend downward into the slot 12 in the bottom of the rail with the heel portion 17' of the finger bearing against the edge 12' in the rail at the end of the slot preventing endwise displacement of the finger outwardly.

As explained above, this is the operative position of the finger and the same prevails with all the fingers. From this position each finger may be turned up, then pivoting on its pivotal mounting 13, to a substantially vertical position when the finger will drop by gravity through the opening 12 in the bottom of the rail to which the finger is adjacent until the edge 19 of the finger engages the mounting 13, the finger then resting on the mounting substantially as shown in Fig. 5, which is the inoperative or out-of-the-way position of the finger.

When thus disposed in its inoperative position the entire finger will occupy a position inside the outer face of the rail which will then function as a guard for all the fingers preventing their being broken as the rack is moved about.

The fingers are maintained in proper operative connection with their respective mountings at all times in any suitable manner but preferably as shown by a flange 22 inturned from the top of the outer side 9 of the rail. This flange has a slot 23 cut in it within which the outer turned end of the finger is contained. As the finger is turned and moved in relation to its mounting it will render or pass through this slot, the flange then functioning to hold the finger in proper operative engagement with its mounting. When the finger has been moved downwardly through the slot 12 to its full inoperative position with the shoulder 19 resting upon the mounting, the back of the finger will then engage the edge 12' at the end of the slot which thus assists in the retention of the finger. From their inoperative or out-of-the-way positions, as shown in Fig. 5, the fingers may be returned to their operative positions as shown in Fig. 4, by drawing up the fingers through the bottoms of the rails until their turned ends engage the mountings when the fingers may be turned down into place.

In the assembling of the parts the fingers are applied to their respective mountings 13 on the rail by an application of the fingers from the under side of the rail, each finger being pushed upwardly through one of the openings 12. To permit of the flanged portion 16 of the finger being thus inserted, the mounting 13 is moved in-

wardly, the openings in the rail through which the ends of the mounting extend being sufficiently large to permit of such movement on loosening the nuts 15. After the fingers are inserted the mounting is moved back into place and the nuts tightened.

Having thus fully described my invention, I claim and desire to secure by Letters Patent of the United States:—

1. In a drying rack, the combination of a base member adapted to support a number of drying units arranged on end, side rails arranged alongside the units, means for supporting the side rails from the base member, fingers carried by the side rails, and means for supporting the fingers whereby each may be moved to have and maintain a down-turned operative position with extension beyond the inner face of the rail carrying the finger or an up-turned inoperative position with extension inside the outer face of the rail.

2. In a drying rack, the combination of a base member adapted to support a number of drying units arranged on end, slotted side rails arranged alongside the units, means for supporting the side rails from the base member, mountings arranged on the side rails above the slots in them, fingers carried by the side rails and having both a pivotal and sliding connection with the mountings whereby each finger may be turned to have and maintain a down-turned operative position with extension beyond the inner face of the rail carrying the finger or an up-turned inoperative position resting upon its mounting with extension in part through a slot in the rail.

3. In a drying rack, the combination of a base member adapted to support a number of drying units arranged on end, slotted side rails arranged alongside the units, means for supporting the side rails from the base member, mountings arranged on the side rails above the slots in them, fingers carried by the side rails and having both a pivotal and sliding connection with the mountings whereby each finger may be turned to have and maintain a down-turned operative position with extension beyond the inner face of the rail carrying the finger or an up-turned inoperative position resting upon its mounting with extension in part through a slot in the rail, and means for retaining each of the fingers in operative connection with its mounting.

4. In a drying rack, the combination of a base member adapted to support a number of drying units arranged on end, slotted side rails arranged alongside the units, means for supporting the side rails from the base member, mountings arranged on the side rails above the slots in them, fingers carried by the side rails arranged upon the mountings, each of said fingers having a

turned end by which it may turn pivotally on its mounting, an edge by which the finger may slide along its mounting, a shoulder by which the finger may engage and rest upon its mounting, and means for retaining each of the fingers whereby it may be turned to have and maintain a down-

turned operative position with extension beyond the inner face of the rail carrying the finger resting in part on said rail or an upturned inoperative position resting by its shoulder on said mounting with extension in part through a slot in the rail. ¹⁰

FREDERICK S. RAY.
